(57) CLAIM

The ornamental design for a watch, as shown and described.

DESCRIPTION

FIG. 1 is a top view of my new, original and ornamental design for a watch;

FIG. 2 is a bottom view thereof;

FIG. 3 is a front view thereof;

FIG. 4 is a rear view thereof;

FIG. 5 is a left side view thereof;

FIG. 6 is a right side view thereof;

FIG. 7 is a front perspective view thereof; and,

FIG. 8 is a bottom perspective view thereof.

The broken lines showing the time in FIGS. 1, 3 and 7 are for illustrative purposes only and do not form part of the claimed design.
